UNITED STATES PATENT OFFICE

165,064

AWNING OR SIMILAR ARTICLE

Nicholas L. Etten, Cedar Falls, Iowa

Application January 16, 1951, Serial No. 13,832

Term of patent 14 years

(Cl. D21—6)

To all whom it may concern:

Be it known that I, Nicholas L. Etten, a citizen of the United States and a resident of Cedar Falls, in the county of Black Hawk and State of Iowa, have invented a new, original, and ornamental Design for an Awning or Similar Article, of which the following is a specification, reference being had to the accompanying drawing, forming a part thereof.

In the drawing:

Figure 1 is a front perspective view of an awning or similar article, showing my new design;

Figure 2 is a side elevational view of the awning; and

Figure 3 is a profile bottom plan view showing generally the cross sectional contour of the canopy of the awning, indicating that the canopy is

made up of separate slats overlapping as illustrated.

I claim:

The ornamental design for an awning or similar article, substantially as shown and described.

NICHOLAS L. ETSEN.
